UNITED STATES PATENT OFFICE.

JOHN E. SOULES, OF LOS ANGELES, CALIFORNIA, ASSIGNOR OF FORTY-NINE ONE-HUNDREDTHS TO D. F. HORGAN, OF LOS ANGELES, CALIFORNIA.

INTERNAL-COMBUSTION ENGINE.

1,183,777.

Specification of Letters Patent. Patented May 16, 1916.

Application filed May 5, 1915. Serial No. 26,170.

To all whom it may concern:

Be it known that I, JOHN E. SOULES, a citizen of the United States, residing at Los Angeles, in the county of Los Angeles, State 5 of California, have invented a new and useful Internal-Combustion Engine, of which the following is a specification.

My invention relates to internal combustion engines and the principal object of the 10 invention is to provide an engine in which the torque on the driving shaft will be more uniform than in the standard engines now on the market.

In my invention I utilize the four stroke 15 cycle, the first stroke drawing in a charge of explosive mixture, the second stroke compressing this mixture, the third stroke utilizing the force of the explosion, and the fourth stroke ejecting the burnt gases.

20 There is thus only one explosion or working stroke to four strokes of the piston and where ordinary cranks and connection rods are used only one working stroke for each cylinder to two revolutions of the crank 25 shaft. In standard designs of engines where several cylinders are used there are half as many working strokes per revolution of the crank shaft as there are pistons. For example, the eight cylinder engine now 30 being applied to several standard motor cars gives four active strokes or impulses per revolution of the engine shaft. In my engine the eight cylinders give eight impulses per revolution of the engine shaft.

35 A further object of the invention is to provide a single opening in each cylinder through which the mixture enters and through which the burnt gases are expelled and to provide in combination with this 40 opening a valve secured directly to the engine shaft thus doing away with the timing gears commonly supplied with internal combustion engine valve gears.

A further object of my invention is to arrange 45 the cylinders at equal distances from the engine shaft and to locate the exhaust and mixture manifolds centrally about the engine shaft so that a very direct path is provided from the carburetor to each cylinder thus doing away with the difficulty, found in many multiple cylinder engines, of getting a uniformly rich mixture in each cylinder.

A further object of my invention is to arrange 55 the cylinders in two pairs with the

working strokes of each pair in opposite directions and to so time the working strokes that a cylinder on one end starts its working stroke before the working stroke of an adjacent cylinder on the other end is completed, thus in a considerable measure 60 balancing the working parts and preventing undue friction.

Further objects and advantages will appear hereinafter or will be evident to one 65 skilled in the art after an examination of the annexed drawings and a perusal of the following specification.

In the drawings which illustrate one form 70 of my invention: Figure 1 is a view of the assembled engine, a portion thereof being shown in section to better illustrate the internal structure. Fig. 2 is a section on the plane x^2-x^2 of Fig. 1 looking in the direction of the arrows. Fig. 3 is an end view. 75 Fig. 4 is a section on the plane x^4-x^4 of Fig. 1 looking in the direction of the arrows. Fig. 5 is a perspective view of a positive rotation valve. Fig. 6 is a perspective view of a negative rotation valve. Fig. 7 is a 80 view of the mixture manifold showing the inlet ports. Fig. 8 is a view of the exhaust manifold showing the exhaust ports. Fig. 9 is a developed view of the cam member.

In the form of my invention illustrated 85 by these drawings a crank case shell 11 is formed in two halves secured together by bolts 12 about upper and lower bearing plates 13 and 14, bearings 15 being formed in the plates 13 and 14 and thrust bearings 90 16 being provided to take any end thrust of a shaft 17 turning in the bearings 15. Rigidly secured to the shaft 17 is the four lobed cam 18 in which is formed the cam groove 19. Four cylinder castings 20 are secured by bolts 21 to the plate 13 and four similar cylinder castings 22 are secured by bolts 23 to the plate 14. Each of the cylinder castings 20 and 22 are provided with a water space 24 through which cooling 95 water may be circulated by any convenient means, not shown. Openings 25 are cut in the base of the cylinder castings 20 and 22 to provide a free opening between the space below the piston and the outer air. 100 105

A piston 26 provided with piston rings 27 slides freely in the bore 28 of each cylinder casting, the pistons each being clamped by nuts 29 on the threaded end 30 of a piston rod 31 so that the amount of compres- 110

sion can be regulated by adjusting the piston on the piston rod. Each of the piston rods 31 passes through a boss 32 formed on one of the plates 13 or 14, packing 33 surrounding the piston rod and being clamped firmly therearound by a gland 34 threaded on the boss 32. A cross head 35 is formed on the lower end of each piston rod, each cross head 35 carrying a roller pin 36 on which a roller 37 is mounted. The ends of the cross heads 35 are so shaped that they engage and are guided by cross head guides 38 these guides having threaded ends 39 passing through holes in the plates 13 and 14 and secured therein by nuts 40, these nuts being located in the openings 25 of the cylinder castings. The cross head guides 38 secure the plates 13 and 14 in their proper relative positions. The rollers 37 fit into the cam groove 19 of the cam 18, the cylinders 20 and 22 being staggered on either end so that the rollers 37 assume the positions shown in dotted lines in Fig. 9 in which the lines 41 indicate diagrammatically the piston rods.

Secured on the shaft 17 is a sprocket 42 for driving a magneto and timing device, not shown. Secured on either end of the shaft 17 are couplings 43 which connect shafts 44 with the shaft 17, the couplings being so made and fitted that they are somewhat elastic so that valve members 45 secured thereon can find their own seat inside a valve ring 46 between an intake manifold 47 and an exhaust manifold 48, the manifolds 47 and 48 being secured to the ring 46 by screws 49. The valve ring 46 is secured by bolts 50 to the cylinder castings 20 and 22, openings 51 being formed in the ring 46 registering with openings 52 communicating with the extreme outer end of the interior of the cylinder castings 20 and 22 and serving both as an intake and an exhaust opening.

The intake manifold 47 and the exhaust manifold 48 are each provided with ports 53 having the same radial central plane as the openings 51. The valve members 45 at either end of the engine each have an intake port 54 formed on one side thereof and an exhaust port 55 formed on the other side, the ports 54 and 55 being 90° apart in each valve and the two valves being so located that the port 54 on one end of the engine is 90° ahead of the port 54 on the other end of the engine. Spark plugs 56 are connected to suitable ignition means driven from the sprocket 42.

The method of operation of the invention is as follows: The shaft 17 being rotated by external means the cam 18 is turned and the rollers 37 in the cam groove 19 are forced up or down by the slope of the groove 19 as shown in Fig. 9. The rollers 37 being

constrained to move along the axis of the piston rods 31 by the cross heads 35 and the guides 38 the pistons 26 are moved up or down in the cylinders. As the pistons 26 move downward on the intake stroke the intake ports 54 connect the openings 51 to ports 53 in the intake manifold 47 which is fed with explosive mixture through a pipe 100. The opening 51 is closed by the rotation of the valve 45 just as the piston 26 completes the intake stroke, the opening 51 remaining closed during the upward compression stroke and the downward firing stroke. The opening 51 is then put into communication with a port 53 of the exhaust manifold 48 through the exhaust port 55 of the valve 45 which turns into the proper position to do this at the beginning of the scavenging stroke remaining open until all the burnt gases are expelled, the port 54 then swinging into position so that the cycle is repeated. The charge is fired at the beginning of the firing stroke by a spark plug 56. In practical operation the various cylinders are fired alternately at either end in the order that their rollers lie in the cam groove 19 so that the piston on one end has not completed its firing stroke before its adjacent piston on the other end receives an impulse. There is therefore a partially balanced pressure on the cam 18. As each piston makes four strokes for each revolution of the shaft 17 each piston gives an impulse once per revolution of the shaft 17. The case 11 is partially filled with oil and ball bearings, not shown, may be provided at various friction points according to standard automobile practice.

I claim as my invention:

1. In an internal combustion engine a plurality of parallel cylinders each having an opening formed in the walls thereof, a shaft parallel to said cylinders, pistons in said cylinders, means by which said pistons drive said shaft, a valve ring secured to said cylinders having a valve bore concentric with said shaft and having a series of peripheral openings each connecting with one of said openings in said cylinders, an intake manifold secured to said valve and having a series of intake ports opening into the bore of said valve ring, an exhaust manifold secured to said valve ring and having a series of exhaust ports opening into the bore of said valve ring, and a flat cylindrical disk rotary valve secured to said shaft, fitting closely in the bore of said valve ring between said intake manifold and said exhaust manifold, and having an intake port and an exhaust port formed therein on either side thereof.

2. In an internal combustion engine a supporting structure, an engine shaft turning in bearings in said structure, a cam member secured to said engine shaft and having a cam groove cut therein, a series of engine

cylinders on one side of said cam member, a series of engine cylinders on the other side of said cam member, a piston in each cylinder, a piston rod for each piston, means for 5 guiding each piston rod along the axis of its cylinder, a roller pin secured to each piston rod, and a roller on each pin, the series of cylinders on one side of the cam member being staggered with relation to the series

of cylinders on the other side of said cam 10 member so that the rollers can engage the cam groove at equal distances about the periphery of the cam member.

In testimony whereof, I have hereunto set my hand at Los Angeles, California, this 15 30th day of April, 1915.

JOHN E. SOULES.
